UNITED STATES PATENT OFFICE.

FREDERICK O. BALL, OF DETROIT, MICHIGAN, ASSIGNOR TO BALL & BALL CARBURETOR COMPANY, OF DETROIT, MICHIGAN, A PARTNERSHIP COMPOSED OF FREDERICK O. BALL AND CORNELIA M. BALL.

CARBURETOR.

Application filed February 15, 1921, Serial No. 445,225. Renewed February 23, 1923.

In the operation of a carburetor it has been found desirable as the velocity of the air through the carburetor passages is reduced to enrich the mixture. One reason for this is that with the slower velocity of air a less proportion of the fuel is thoroughly atomized. Another reason is that a low velocity through the carburetor is usually accompanied with a desire for a more powerful mixture as where an automobile on which the carburetor is used is ascending a grade. Devices for enriching the mixture continuing with this condition of low velocity have come to be called step-up devices.

It has also been found desirable on the sudden change of velocity as where the throttle is opened to momentarily augment the fuel delivered. Such devices have come to be known as pick-up devices.

It is desirable to have these devices automatically actuated through the variation in pressure, particularly a variation at the discharge side of the throttle so that such devices will operate only when the condition exists making their operation desirable. The present invention is designed to so operate.

The invention is illustrated in the accompanying drawing which shows a central section through the carburetor.

1 marks the float chamber, 2 the float, 3 the inlet valve, 4 the inlet connection, 5 mechanism for communicating the movement of the float to the valve, 6 the cover, and 7 the clip for holding the cover in place.

The float chamber has a projection 8 extending under the body of the carburetor and secured to the body of the carburetor by a screw 9 which extends through the projection 8 and forms a closure for a chamber 10. The screw has a reduced portion forming a passage 11 which communicates with a passage 12 leading from the float chamber. A passage 13 extends into the body of the carburetor from the passage 11 and communicates with a passage 14 leading to the nozzle 15. The nozzle is arranged in a Venturi tube 16 forming an initial air opening of the carburetor. The Venturi tube opens into the mixing chamber 17. An auxiliary air opening 18 is provided. This is controlled by a yielding valve 19 operating on the seat 20. The valve is guided by a pin 21 extending from a cap 22. A spring 23 yielding holds the valve to its seat. A

throttle valve 24 is arranged on a stem 25. A choke valve 28 is mounted on the stem 29 and controls the air inlet in the usual manner.

The screw 9 has a radial opening 9^a which forms a means of communication between the passage 11 and an axial opening 9^b in the screw 9. The passage 9^b extends upwardly in a cylindrical extension 30 projecting upwardly from the screw 9. This is connected by radial openings 31 with the chamber 10. A needle valve 32 operates on the seat at the upper end of the passage 9^b. This valve has a restricted opening 32^a forming a restricted communication between the passage 9^b and the interior of the cylinder 30 when the valve is seated. The valve 32 has a stem 33 which extends upwardly through a passage 34 in the screw cap 34^a secured in the upper end of the extension 30. A spring 35 is arranged around the stem 33 and operates against the back of an enlargement 36 forming a valve which controls the passage 34. The valves 32 and 36 are so distanced with relation to the distance between their seats that when the valve 36 is closed the valve 32 is opened and vice versa, the spring 35 tending to close the valve 36 and open the valve 32. The stem 33 engages enlarged head 38 of a plunger 39. The plunger 39 operates in a cylinder 40. The cylinder 40 is connected by a passage 41 with the carburetor or suction passage above the throttle. A spring 42 operates against the shoulder 38 and is of sufficient strength to overcome the spring 35 and close the valve 32 when the parts are not influenced by the piston or plunger 39. The passage 34 communicates with a passage 37 and this chamber communicates through a passage 43 with the mixing chamber or suction passage of the carburetor above the throttle. A passage 44 leads from the upper end of the chamber 10 to the outer air.

The operation of the device is as follows: When the throttle is closed and the engine running the pressure above the throttle is very much reduced and this reduced pressure being communicated through the passage 41 to the cylinder 40 subjects the upper face of the piston or plunger 39 to a less pressure than that below the piston sufficient to overcome the spring 42 and as the shoulder 38 moves upwardly the stem 33 follows up under the influence of the spring 35, thus clos-

ing the valve 36 and opening the valve 32. The reduction above the piston 39 to accomplish this action is such as to take place in the usual or normal operation of the carburetor and it is only with a comparatively wide open condition of the throttle that the piston will descend reversing the valves 32 and 36.

The resultant action so far as the fuel is concerned through this operation of the valve is as follows:—With the valve 36 closed the supply of fuel is confined to the nozzle 15. When the reversal takes place and the valve 36 is opened and the valve 32 closed a quantity of gasoline which is accumulated in the chamber 10 and within the cylinder 39 is immediately carried up through the passage 34 and passage 43 to the mixing chamber. This is accomplished through the higher pressure of air admitted through the passage 44. This momentary augmenting of the fuel accomplishes what is ordinarily termed a pick-up. A restricted flow of fuel continues through the passage 32^a in the valve 32 and this is carried up with the air entering through the passage 44 and passes through the chamber 10, passages 31 and upwardly with the fuel through the passage 34 and into the mixing chamber by way of the passage 43. This added fuel is continued so long as the valve 32 remains seated and the valve 36 open and accomplishes what is commonly termed a step-up operation, that is, there is an enriching of the mixture which continues so long as the condition above described continues.

With the exception of the step-up feature of this construction the carburetor here shown is a duplicate of the carburetor shown in my Reissue Patent #14,790, Jan. 13th, 1920.

What I claim as new is:—

1. In a carburetor, the combination of a body having a suction passage; means for supplying a combustible mixture to the passage comprising as elements fuel and air; devices for varying the supply of one of the elements of the mixture to vary the proportions of fuel and air, said devices being controlled by a pre-determined variation of the pressure in the suction passage whereby the mixture is enriched as the velocity through the passage is reduced; and means for momentarily augmenting the proportion of fuel at the moment the velocity is reduced.

2. In a carburetor, the combination of a body having a suction passage; means for supplying a combustible mixture to the passage comprising as elements fuel and air; devices for varying the supply of one of the elements of the mixture to vary the proportions of fuel and air, said devices being controlled by a predetermined variation of the pressure in the suction passage whereby the mixture is enriched as the velocity through

the passage is reduced; and means acting with said devices for momentarily augmenting the proportion of fuel at the moment the velocity is reduced.

3. In a carburetor, the combination of a body having a suction passage; means for supplying combustible mixture to said passage comprising as its elements fuel and air; a step-up device; a pick-up device; and means for actuating said devices through a variation of pressure in the suction passage.

4. In a carburetor, the combination of a body having a suction passage; means for supplying combustible mixture to the passage comprising as elements fuel and air; means for varying the supply of fuel to vary the proportions of fuel and air, said devices being controlled by a predetermined variation of pressure in the suction passage whereby the mixture is enriched as the velocity through the passage is reduced; and means for momentarily augmenting the fuel at the moment the velocity is reduced.

5. In a carburetor, the combination of a body having a suction passage; a throttle in the passage; mean for supplying combustible mixture to said passage comprising as its elements fuel and air; a step-up device; a pick-up device; and means for actuating said devices through a variation of pressure in the suction passage at the discharge side of the throttle.

6. In a carburetor, the combination of a suction passage; means for delivering combustible mixture comprising as its elements, air and fuel to said passage; pick-up and step-up devices, said devices enriching the mixture by augmenting the fuel and acting by a direct action of inflowing air upon said fuel; and mechanism responsive to variations of pressure in the suction passage actuating said devices.

7. In a carburetor, the combination of a suction passage; means for delivering combustible mixture comprising as its elements, air and fuel to said passage; pick-up and step-up devices, said devices enriching the mixture by augmenting the fuel and acting by a direct action of inflowing air upon said fuel; and mechanism responsive to variations of pressure in the suction passage actuating said step-up device.

8. In a carburetor, the combination of a suction passage; a throttle valve; means for delivering combustible mixture comprising as its elements air and fuel to the passage; pick-up and step-up devices acting through a direct action of the air on fuel delivered to the suction passage; and mechanism responsive to variations of pressure in the suction passage at the discharge side of the throttle actuating said step-up device.

9. In a carburetor, the combination of a suction passage; a throttle valve; means for delivering combustible mixture comprising

as its elements air and fuel to the passage; pick-up and step-up devices acting through a direct action of the air on fuel delivered to the suction passage; and mechanism responsive to variations of pressure in the suction passage at the discharge side of the throttle actuating said devices.

10. In a carburetor, the combination of a suction passage; means for delivering air and fuel to the suction passage comprising a chamber communicating with the suction passage with a fuel supply and having air passages leading to an air supply; and valve mechanism responsive to variations of pressure in the suction passage controlling the flow from said chamber to the suction passage to supplement the fuel supply in the suction passage momentarily with a pick-up action upon the reduction in velocity through the suction passage and to augment the fuel supply to the suction passage with a step-up action continuing so long as there is a reduction of velocity in the suction passage.

25 11. In a carburetor, the combination of a suction passage; a throttle in the suction passage; a pick-up device; and a step-up device comprising a valve mechanism responsive to variations of pressure at the discharge side of the throttle.

30 12. In a carburetor, the combination of a suction passage; pick-up and step-up devices comprising a chamber, said chamber having communication with the atmosphere; a valved inlet leading to the chamber having a restricted bypass; a valved outlet lead-

ing from said chamber to the suction passage; valves controlling said inlet and outlet; and means responsive to variations of pressure in the suction passage controlling said valves.

13. In a carburetor, the combination of a suction passage; a throttle in said suction passage; a cylinder communicating with the suction passage above the throttle; a piston in the cylinder; a chamber communicating with a fuel supply; a valve controlling the communication to the fuel supply; a restricted bypass between the chamber and the fuel supply; an outlet from said chamber leading to the suction passage; a valve controlling the outlet; and means acting with the piston for actuating said valves.

14. In a carburetor, the combination of a suction passage; a throttle in the suction passage; a cylinder communicating with the suction passage at the discharge side of the throttle; a piston in the cylinder; a spring opposing the piston; a chamber having a fuel connection; an outlet leading from the chamber to the suction passage; an inlet leading to the chamber from the atmosphere; valves controlling the fuel supply leading to the chamber and the outlet; means tending to hold the valves in position to close the outlet; a restricted bypass leading from the fuel supply to the chamber; and a connection between the valves and the piston.

In testimony whereof I have hereunto set my hand.

FREDERICK O. BALL.
